UNITED STATES PATENT OFFICE.

WILLIAM BEATTIE, OF PORTAGE, WISCONSIN.

FOOT AND LEG PROTECTOR.

SPECIFICATION forming part of Letters Patent No. 283,193, dated August 14, 1883.

Application filed May 7, 1883. (No model.)

To all whom it may concern:

Be it known that I, WILLIAM BEATTIE, of Portage, in the county of Columbia, and in the State of Wisconsin, have invented certain new and useful Improvements in Foot and Leg Protectors; and I do hereby declare that the following is a full, clear, and exact description thereof.

My invention relates to coverings for the foot and leg, adapted for use in very cold weather in northern latitudes, and is in part an improvement on the device patented by me on the 8th of February, 1881; and it consists in certain peculiarities of construction, as will be more fully set forth hereinafter.

In the drawings, Figure 1 is a perspective view of my present invention, opened out to enable it to dry readily after use; and Fig. 2 is a like view of the same, but showing it in the closed position, as it is when in use.

In my former device, described in the patent above named, the protector was designed to be worn outside of the pantaloons, and for that reason the leg or upper was made of a single piece of sheep-skin, as the fullness of the folded skin afforded ample room for the trousers' legs; but my present invention is intended to be worn under the pantaloons, and hence the leg part is made of two equal portions, A and A', united by central back seam, a, and thereby adapted to fit closely to the leg of the wearer; and the foot portion consists of the sole B and the uppers C C', which latter are made of two equal portions united to the sole B by the seam b, and to the leg portions by the seams c and c', and adapted to open out to the toe of the wearer. The entire article, like my former device, may be made of tanned sheep-skin with the wool on, or of any other suitable warm material.

The former device was made with a flap to overlap the front opening, and the whole secured by straps and buckles; but this necessitated that each pair of the protectors should be made "rights" and "lefts," which is more or less objectionable, and I have hence dispensed with the flap and with the straps and buckles, and therefore either protector may be worn indifferently on either leg, and it is immaterial

which leg and foot section A C or B' C' overlaps the other.

A further advantage of my present device is that it opens out more fully than my old protector, and hence dries more readily.

Instead of buckles and straps, (which, as stated, required the protectors to be rights and lefts, as they had to be on the outer sides of the legs to avoid interference,) I provide my present device with hooks or buttons d d, and extend a single lacing-cord, D, from one of the lower hooks or buttons d around back of each one, and so to the next, and thence up to the top, where it may be wound around the leg and then fastened, as shown. The pantaloons may now be pulled down over the protector, and I propose that "arctic" overshoes or rubbers be worn over the protector in preference to boots. The protector is entirely concealed from sight, and thus obviates an objection that some have made to my previous device.

I consider my present device a great improvement over any now made, so far as known to me, and deem the feature of opening out all the way to the toes of primal importance.

Having thus described my invention, what I claim as new, and desire to secure by Letters Patent, is—

1. A foot and leg protector with a central front opening extending all the way to the toe, so and provided with a sole, substantially as shown and described.

2. A foot and leg protector consisting of two equal leg portions united by central back seam, and two equal foot-uppers united to the leg portions and to the sole, and open all the way to the toe, and adapted to fold over either to the right or left, substantially as shown and described.

In testimony that I claim the foregoing I have hereunto set my hand, on this 3d day of January, 1883, in the presence of two witnesses.

WILLIAM BEATTIE.
